UNITED STATES PATENT OFFICE.

JOHN A. TOOMEY, OF LOS ANGELES, CALIFORNIA.

INTERNAL-COMBUSTION ENGINE.

1,250,715.

Specification of Letters Patent. Patented Dec. 18, 1917.

Application filed November 2, 1915. Serial No. 59,214.

To all whom it may concern:

Be it known that I, JOHN A. TOOMEY, a citizen of the United States, and a resident of Los Angeles, in the county of Los Angeles and State of California, have invented certain new and useful Improvements in Internal-Combustion Engines, of which the following is a full, clear, and exact specification.

- 10 My invention relates to two cycle engines and to novel means for scavenging and carbureting the same, so as to separate these operations and have them follow each other in the cycle.
- 15 The invention preferably applies to engines having four or a multiple of four cylinders, and with cylinders having pistons of two diameters, one working in the explosion chamber and the other in an air compressing chamber, but the invention may be applied to other designs of engines without departing from the claims of this invention.

In the accompanying drawings, Figure 1 is a diagrammatical drawing of an explosion engine, and shows the relation and position of the various parts of this invention.

Fig. 2 is a plan view of a four cylinder engine. Cylinders 1 and 2 showing the scavenging air passages and 3 and 4 the carbureting air passages, with valves and connections.

Similar numbers refer to similar parts in all the drawings.

Referring to the drawings, A is the cylinder, B is the engine base, C the crank, E the exhaust manifold, P the piston, D an air deflector, cast as part of the cylinder head, S the spark plug, 26 the throttle control lever, W the water jacket, which together with all the accessories needed to make a complete combustion engine are used in combination with the improvements hereinafter described.

The cylinder A and piston P are made with two diameters, one working in the explosion space 7 and the other in the air compression chamber 8. The air compression space 8 has the inlet valve 9, and exhaust passages hereinafter described. The explosion space 7 has the exhaust port 10, the air scavenging port 11 and the carbureted air port 12 all of which are opened and closed by the piston movement as will be further described.

Cylinders 1 and 2 are paired and have 55 their cranks set at an angle of 180 degrees. The air compression space 8 of cylinder 1 is connected with the explosion space 7 of cylinder 2 by the air conduit 15. In like manner cylinder 2 is connected with cylinder 1, by the conduit 14.

Cylinders 3 and 4 are paired, similar to 1 and 2, the air conduits being indicated by the dotted line 16.

The compression space 8 of each cylinder 65 has an air connection 17 into an air conduit 18, said space 8 of each cylinder being closed against back pressure from adjoining cylinders by a check valve 19. The conduit 18 is common to all of the cylinders and conveys the air through the throttle 20 for control, and then through the carbureter 21 into the manifold 22 where it is distributed to the various cylinders, entering the explosion space 7 through the port 12 of each 75 cylinder.

The cranks of cylinders 1 and 2 are set at an angle of 90 degrees with the cranks of cylinders 3 and 4.

If the piston P shown in Fig. 1 be considered as piston 1, the relative position of piston 2 is indicated by the dotted lines 22 and of 3 and 4 by the dotted lines 23. This, together with the previous described construction, gives the following cycle. As the 80 piston 1 descends on the explosion stroke, it first uncovers the port 10 exhausting the pressure, it then uncovers the port 11 and the compressed air in the compression space 8 of cylinder 2 passes through the connecting 90 passage 14 into explosion space 7 of cylinder 1 and out of port 10 scavenging it of burnt gas. The piston 1 will now uncover the port 12 and as the piston 3 is at about half of the compression stroke, compressed 95 air will pass from the cylinder 3 through the connection 17 and valve 19, the air conduit 18, the throttle 20, the carbureter 21, the manifold 22 and port 12 into the explosion space of cylinder 1 as an explosive gas. 100 This gas will displace an equal amount of air in the cylinder which will be exhausted through port 10; compression and explosion follow in turn.

During this cycle cylinder 4 is on the explosion or downward stroke and the air compressor is drawing in a supply of air through the valve 9. As cylinder 4 com-

2
plete the explosion-stroke, cylinder 3 completes the compression stroke and cylinder 1 is at the half compression stroke and the same cycle is completed for cylinder 4, and 5 in like manner for each cylinder in turn.

The throttle 20 regulates the amount of air taken from the compressors for carbureting purposes and the mixture will be very "rich" or "lean" as more or less air is 10 diverted. The dimensions of the space 24 which forms part of the compression space 8 regulates the pressure of the air used for scavenging the cylinders.

The carburation of this engine differs 15 from others in that it is effected by pumping air through the carbureter instead of drawing air through by suction. Various forms of mixing devices may be used. I prefer and have shown what is known as a 20 "puddle" carbureter, which consists of bowl 30 divided by the wall 31. Gasolene enters the bowl 30 through the opening 32, the flow being regulated by the set screw 33 and the height 36 regulated by the float 34 and 25 valve 35.

The air enters the carbureter from the throttle 20 and is forced downward by the wall 31 against the "puddle" 36 of gasolene in the bottom of the bowl, spraying and 30 breaking it up and carries with it a portion of the gasolene into the cylinders.

Gasolene is supplied the carbureter by the tank 40, through the piping 42, and as it must feed against a pressure of air, the air 35 conduit 18 is connected with the tank 40, by the piping 41, equalizing the pressure in both. A check valve 45 is placed in the piping 41 to provide an even pressure in the tank 40 as the pressure varies in the carbureter as each cylinder is charged. Advantage 40 may be taken of this variation in pressure to feed the gasolene from a lower level than the carbureter if desired.

I claim:

45 1. The combination in an explosive engine, of a plurality of cylinders, each having two diameters, and each having a working piston with similar diameters reciprocating therein, one diameter of the piston working 50 in the explosion chamber, the other diameter working in an air compression chamber, said explosion chamber having an exhaust port, a port for scavenging air, and a port for carbureted air, said ports designed to be 55 opened successively, by the downward movement of the piston, and to be closed in a reverse order by the upward movement of the piston, said compression chamber having a valve for the suction of air into the 60 chamber, and an air outlet into an air conduit, an air conduit, a manifold, said air conduit connecting the compression spaces of all of the cylinders, an automatic check valve closing each compression space against 65 air from the conduit, said air conduit de-

signed to convey air from all the compression cylinders into the manifold, said manifold common to all the explosion cylinders and designed to distribute said air to the carbureted air ports of each cylinder, a 70 throttle in said air conduit, means for operating the throttle to regulate the quantity of air, a carbureter forming part of said air conduit, designed to carburet all air passing through it, said air conduit, throttle, carbureter and manifold and their connections designed to retain air under pressure, said plurality of cylinders being designed in pairs, and the compression space of each cylinder, having an air connection, with the 80 explosion space of the paired cylinder, through the scavenging air port of said cylinder, a crank shaft, said crank shaft having the cranks set at suitable angles to provide a series of cylinders whose suction 85 and compression will coincide with and provide air for scavenging and carbureting each cylinder in turn, a tank for storing an explosive element, means for equalizing the pressure in the tank air conduit and carbureter, means for conveying said explosive element into the carbureter to carburet the air passing into the explosion chamber, means for controlling the flow of said explosive element into the carbureter, means for exploding said carbureted air in the explosion chamber and a connecting rod for applying the force of said explosion to the crank shaft of the engine, substantially as described. 95

2. In an explosion engine, an air conduit for conveying compressed air from a compression chamber into the explosion chamber and a carbureter for carbureting said air, a fuel supply tank, a float to control the flow 105 of fuel to the carbureter, and a means for equalizing the air pressure in the carbureter, fuel supply tank and air conduit, substantially as described.

3. In an explosive engine, the combination of two or more pairs of cylinders, each cylinder having an explosion chamber and an air compression chamber, a piston in each cylinder working in both chambers, each explosion chamber having an exhaust outlet 110 and an inlet for scavenging air and air inlet for carbureted air, all controlled by the piston movement, said pairs of cylinders having the compression space of each cylinder connected with the scavenging air inlet 115 of the paired cylinder, an air conduit connecting all the air compression chambers, with the carbureted air inlet of each cylinder, designed to convey air from the air compression chamber having the highest 120 pressure to the air inlet of the cylinder to be carbureted, a carbureter, said carbureter forming part of said air conduit, a fuel tank, and means for controlling and feeding said fuel to the carbureter, under pressure and 125 130

means for controlling the passage of air through the air conduit, substantially as described.

4. In an internal combustion engine having compression cylinders and explosion cylinders, an air conduit between said compression cylinders and explosion cylinders, a trap formed in said conduit to hold an explosive element, a wall in said trap to deflect the air against said explosive element, a reservoir for said explosive element surrounding and part of said trap, an opening in the bottom of the trap into the reservoir for admission of gasolene, a needle valve to regulate said opening, a float con-

trolled mechanism to regulate the height of the explosive element in the reservoir and trap, a supply tank for said explosive element, connecting with said reservoir to supply the explosive element, an air connection 20 between the air conduit and said tank to equalize the air pressure in each, a check valve in said air connection, and a throttle in said air conduit to regulate the air supply, substantially as described.
